United States Patent Office.

WILLIAM SNODGRASS, OF MACOMB, ILLINOIS, ASSIGNOR TO HIMSELF
AND JAMES STATLER, OF SAME PLACE.

Letters Patent No. 66,405, dated July 2, 1867.

IMPROVEMENT IN WAGON-HUB BORING MACHINE.

The Schedule referred to in these Letters Patent and making part of the same.

TO ALL WHOM IT MAY CONCERN:

Be it known that I, WILLIAM SNODGRASS, of Macomb, in the county of McDonough, and State of Illinois, have invented a new and improved Machine for Boring Hubs for Wagons, &c.; and I do hereby declare the following to be a full and correct description of the same, sufficient to enable others skilled in the art to which my invention appertains to fully understand and use the same, reference being had to the accompanying drawings, making part of this specification, and in which—

Figure 1 is a plan of my improved machine.

Figure 2 is a longitudinal vertical section of the same, in line *x x*, fig. 1.

Figure 3 is a detached view of part of the same hereinafter described, and

Figure 4 is a cross-vertical section, on the line *y y*, fig. 1.

Similar letters of reference indicate corresponding parts in the several figures.

The nature of my invention consists in so pivoting the frame *A* in which the chuck on the working-shaft is held that the position of the hub towards the cutting-bar may be varied according to the size and shape of the bore required; further, in connecting the two chucks between which the hub is held by means of a strap, one end being attached to each chuck; also in a novel way of giving motion to the carriage holding the cutting-bar, and automatically throwing the same out of gear when the bore is made; and lastly, in novel means of laterally adjusting the pivoted cutting-bar.

A, in the drawings, represents the main frame of my machine, on the top plates *B B'* of which the carriage *C* slides. This carriage has on its front end two uprights, *D D*, which form bearings for the stationary screw *E*, provided with a hand-wheel, *F*, by means of which the screw is operated. Loose on this screw, between the uprights *D D*, is a nut, *G*, provided at its top and bottom side with a pin, *a*, each working in a slot, *b*, in the forked end *c c* of the cutting-bar *H*, which is pivoted at *d* on the rear end of the carriage *C*, to one side of which is attached a spring, *I*, the free end of which terminates in a flat piece, *J*, sliding on and firmly pressed against the top plate *B* to steady the movement of the carriage. To an upright, *K*, on the opposite side of the carriage, a slotted plate, *L*, is secured by means of the set-screw *e*, so that the plate *L* can be set forward or back at pleasure.

At the rear part of the frame *A* are the uprights *M M'*, braced by the cross-pieces *N N'*, which latter are provided at their centre with openings forming boxes for the journals *O O'* of the yoke *P*, in which the central chuck *Q* moves freely on bearings or friction-rollers, being held by projections *f f* on both sides of the yoke. The chuck *Q* is provided at its rear with a screw-thread, *Q'*, and over it is a semicircular brace, *R*, attached to the uprights *M M'*, and forms bearings for the set-screws *g g'*, the rear ends of which bear against the yoke *P*.

S S are horizontal pieces firmly attached to the journals *O O'* of the yoke, and braced by the uprights *T T'*, in which latter are the bearings of the working-shaft *U*, which, between the uprights *T T'*, is provided with a screw-thread, *h*, on which two nuts, *i* and *k*, move, which serve to set the shaft *U*, at the front end of which is a conical chuck, *V*. The two chucks are each provided with a loop, *l*, and connected to each other by a strap, *m*, having hooks at its ends which hook into the loops *l*, as shown in fig. 1.

Pivoted in the horizontal pieces *S S'* are two braces, *W*, the front ends of which are provided with slots, *n*. Set-screws *o* passing through the slots *n* and into projection *p* on the uprights *M M'*, hold the braces securely.

Grasping the journal *O*, and securely attached to the same, is the cross-bar *q*, provided with three upright pieces, *r r¹ r²*, in the first two of which are the bearings of the hollow shaft *s* bearing the toothed wheel *s'*, to which motion is imparted by the screw-thread *Q'* on the front of the chuck *Q*. Into the hollow shaft *s* fits the small end of the sliding-shaft *s²*, which has its outer bearing in the upright *r²*, and is moved by a hinged piece, *t*, grasping the end of the shaft *s²*. This piece *t* is provided at its top with a pin, *t'*, moving in an oblique slot in the sliding piece *t²*, which again is moved by the lever *a*. The wheel *s'* is provided with a pin, *s³*, and the shaft *s²* with a pin, *s⁴*, so that when the shaft *s²* is moved towards the shaft *s*, the pin *s³* will strike against the pin *s⁴* and force the shaft *s²* to revolve. On this latter shaft *s²* is fastened a rope or chain, *u*, the other end being attached to the carriage *C*. An elbow-lever, *w*, is pivoted to the top plate *B* of the frame *A* in such a manner that when the plate *L* strikes its arm *w'* the other arm will move the lever *a*, and thus throw the shaft *s²* out of gear with the shaft *s*.

The operation of my machine is as follows: The nuts *i* and *k* are turned forward on the shaft *U*, which allows the latter to be drawn back, so that the hub to be bored can be placed between the two chucks *V* and *Q*. The nut *i* is then turned back, forcing, as its rear end begins to bear against the upright *T*, the shaft *V*, bearing the chuck *V*, forward towards the chuck *Q* until the hub is firmly held between the two. The nut *k* is then turned back, and serves to hold the nut *i* from revolving on the shaft. The strap *m* is now hooked on to the chucks, and motion applied by any suitable means to the shaft *U*. The carriage, at this point of the operation, is at the extreme front of the frame *A*, and the lever *a* pressed in towards the frame, thus connecting the shaft *s*² with the shaft *s*¹. As the chuck *Q* revolves the screw-thread *Q'* revolves the toothed wheel *s*¹, and with it the shaft *s*², which winds up the rope *u*, and draws the carriage *C* to the rear. The cutting-bar *H* meanwhile cuts the hole into the hub.

When the carriage has moved forward to that point where the plate *L* strikes the arm *w'* of the bell-crank lever *w*, its other arm moves the lever *a* and disconnects the shaft *s*³ from the shaft *s*, thus stopping the carriage. The plate *L* being provided with a slot, the same can be set so as to always strike the lever *w* when the cutting-bar *H* has made the hole through the hub.

The cutting-bar *L* being pivoted to the front of the carriage can be set at an angle to the hub by means of the screw-shaft *E*. But when the cutting-bar is set obliquely to the hub, when the latter is in direct line with the rear frame, and at right angles with the rear end of the carriage, the hole bored would be a perfectly straight one. To bore a conical hole into the hub the rear frame, attached to the journals *O O'* of the yoke *P*, is moved laterally, after loosening the screws *o*, and allowing the braces *W* to move by means of the slots *n*, by means of the set-screws *g g'*, one of which is screwed out, while the other is screwed in, in proportion. Both screws being tightened when the frame is in the desired position, the latter is securely and firmly held by the braces *W*, the screws having been tightened again. The cutting-bar in boring the hole comes nearer and nearer to the centre of the hub, according to the position given to it and the frame, which, of course, will make the bore conical. By adjusting the cutter-bar by means of the screw *E*, it may be made to cut light or heavy, as desired, and by adjusting the rear frame the hole may be bored more or less tapering to fit the box.

In operating my machine I place the hub between the chucks after the spokes are put in and the felloes are on. It then acts as a fly-wheel, and assists in giving steadiness to the motion; and I am also able to cut off the ends of the spokes if they project too far within the hub.

Having thus described my invention, what I claim, is—

1. The laterally adjustable frame, having the chucks *V Q* mounted therein, in combination with the cutting and feeding mechanism, arranged to operate as and for the purpose set forth.
2. The cutter-bar *H*, pivoted upon the front end of the carriage *C*, in combination with the screw-rod *E* mounted on the carriage, and arranged to operate the cutter-bar as described.
3. The strap *m*, or its equivalent, arranged to unite the independent chucks *V* and *Q* for the purpose of causing both to revolve together when motion is applied to one, substantially as herein set forth.
4. Feeding the cutter-bar to its work by means of the screw-thread *Q'* on the chuck *Q*, wheel *S'* mounted on the shaft *S*, and cord *u* attached to the carriage *C*, when said parts are arranged to operate as herein shown and described.

WM. SNODGRASS.
